UNITED STATES PATENT OFFICE.

LAURENCE RAYNOLDS, OF NEW YORK, N. Y.

AEROPLANE.

Application filed June 27, 1924. Serial No. 722,634.

My invention relates to aeroplanes and has for its object to provide an improved sustaining plane construction, whereby the sustaining planes may be easily adjusted to the most efficient flight positions and, when necessary, utilized as braking means for bringing the aeroplane to a quick stop upon the ground. Other more specific objects will appear from the description herein-
10 after, the features of novelty being pointed out in the claims.

In the accompanying drawings, which show examples of the invention without defining its limits, Fig. 1 is a plan view of the 15 aeroplane constructed in accordance with my invention and showing one of the sustaining planes stripped of its covering; Fig. 2 is an end view of the aeroplane with the sustaining planes in positions to act as 20 brakes for retarding and stopping the machine; Fig. 3 is a fragmentary sectional view on the line 3—3 of Fig. 4; Fig. 4 is a fragmentary sectional view on the line 4—4 of Fig. 3; Fig. 5 is a detailed sectional view 25 on the line 5—5 of Fig. 3; Fig. 6 is a sectional view on the line 6—6 of Fig. 3; Fig. 7 is a side elevation of the aeroplane as it appears in flight; Fig. 8 is an enlarged detailed section on the line 8—8 of Fig. 2; Fig. 30 9 is a detailed face view of another form of sustaining plane.

As shown in the drawings, the aeroplane comprises the customary body or fuselage 10 constructed in any customary manner and including the conventional running gear 11 and device 12 for adapting the machine to travel upon the ground. The aeroplane is driven by means of the usual internal combustion engine 13 and propeller 14, it being understood that such other elements and contrivances as are customarily found in aeroplanes may be included in the construction in any well known way. Braces 15 and 16 are connected with the forward end of the body 10 and project outwardly and rearwardly therefrom as shown in Figs. 1 and 2, said braces terminating in bearings 17 which, as shown in Fig. 8, are rearwardly offset with respect to the braces for the purpose to be more fully set forth hereinafter; 45 suitable provision is made to maintain these bearings 17 against shifting to the right and left in Figs. 1 and 2, in order to provide the desired stability of structure. The bearings 17 constitute journals for hollow shafts 18 upon which suitable frames 19 are fixed; the

frames 19 are covered with aeroplane cloth or other suitable material 20 to provide main sustaining planes or aerofoils located upon opposite sides of the body and projecting in opposite directions therefrom. It will be understood that the number and arrangement of main sustaining planes is determined by the character of the aeroplane; that is, whether the same is a monoplane, as shown in the illustrated example, or a biplane, to which the invention is equally well adapted. The hollow shafts 18 are further journaled in, and extend inwardly beyond, bearings 21, suitably located upon the framework of the body or fuselage 10, as shown in Fig. 6. At these inwardly projecting ends, the hollow shafts 18 are provided with bevel gears 22 which mesh with bevelled pinions 23 carried by upright shafts 24. The latter are rotatably mounted in suitable bearings 25, fixed upon the framework of the body 10, and, at their lower ends, are provided with bevelled pinions 26, which are in mechanical engagement with bevel gears 27 fixed upon a shaft 28; the latter is journaled in bearings 29, suitably mounted upon the framework of the body 10, as shown in Fig. 4. An operating lever 30 is rigidly mounted upon the shaft 28 so as to be capable of imparting a rocking motion thereto for the purpose to be more fully set forth hereinafter. In order that the parts controlled by the lever 30 may be locked in adjusted positions, suitable locking mechanism may be provided; in the illustrated example, this mechanism comprises a spring controlled latch 31 mounted upon the lever 30 and arranged for cooperation with notches 32 of a quadrant 33 fixed upon the framework of the body 10 adjacent to said lever. A finger lever 34 may be pivotal mounted upon the lever 30 for adjusting the latch 31 to an inoperative position or, other words, for releasing the locking mechanism, the latter being automatically stored to its operative position by the tension of its spring. In addition to the pilerons 35 which, as shown in Figs. 1 and 2, are mounted upon shafts 36 extending through and beyond the hollow shafts 36, To provide the necessary stability in shafts 36, bearing sleeves 37 may be provided at spaced intervals throughout hollow shafts 18, as shown in Fig. 7; their inner ends, the shafts 36 are pr-

with arms 38, the free ends of which are pivotally connected at 39 with links 40, which in turn are pivotally connected at 41 with a rocking lever 42, pivotally mounted at 43 upon the body 10 of the machine. The operation of the rocking lever 42 is controlled by means of the stick 44, which is connected with the lever 42 so as to be capable of pivotal movements relatively thereto; the pivot lever 43 is preferably in the nature of a universal joint. The stick 44 in addition to controlling the operation of the lever 42, and consequently the ailerons 35, is operatively connected by means of a connection 45 with the horizontal rudder 47, so as to operate the same in harmony with the ailerons 35 in the usual manner; a connection 46 leads from the vertical rudder 48 to the customary foot controlled rudder-bar located, as usual, in the fuselage and omitted from the present drawings simply to avoid complicating the same. In the form shown in Figs. 1 and 2, the ailerons 35 are located beyond the outer ends of the sustaining planes 20 and are mounted in protecting frames 49, which are secured to, or the sustaining planes 20. To increase the stability of the ailerons 35, the shafts 36 thereof may be journaled at 50 in said protecting frames 49 as shown in Figs. 1 and 2. In the form shown in Fig. 9, the ailerons 35^a are located within the confines of the sustaining planes 20^a, the latter being provided with suitable apertures 51 for the accommodation of said ailerons as shown in said Fig. 9.

With the arrangements set forth, the main sustaining planes 20 or 20^a are mounted upon the body or fuselage of the aeroplane so as to be capable of being pivotally swung entirely from normal sustaining positions through arcs of not less than 90 degrees. This is accomplished by operating the lever 30 toward the right in Fig. 3, so as to correspondingly rock the shaft 38 and thereby causing about a similar actuation of the bevel gears 37. The movement of the latter is communicated to the pinions 26 and shafts and to the pinions 23, which in turn actuate the gears 22 and the hollow shafts 18 thereby adjust the sustaining planes 20^a from the position shown in solid lines Fig. 3, to the upright position *a*, shown dotted lines in said figure, or to any angle intermediate of these two positions. The planes 20 or 20^a are locked in adjusted position by means of the latch 31 and the notches 32 of the fastener 33. It is thus possible to easily the sustaining planes 20 or 20^a to positions most advantageous to exist atmospheric conditions and to secure best efficient flying conditions. In ad-

ditions to this, when the plane reaches the ground, the sustaining planes 20 or 20^a may be shifted through arcs of not less than 90 degrees to positions in which the surfaces thereof are presented in opposition to the direction of travel or, in other words, extend in directions at approximately right angles to said direction of travel. The planes thus interpose a vigorous resistance to the air and thereby exert a braking action on the aeroplane and bring it to an almost immediate stop. The sustaining planes 20 or 20^a are also capable of being dipped to a limited extent, for instance, from the solid line position shown in Fig. 3 to the dotted line position *b* shown therein.

In order to permit the movements of the planes 20 or 20^a necessary to the adjustments from the solid line position *a* therein, the planes are provided with suitable openings 20^b in registry with the bearings 17 as shown in Fig. 2; this degree of movement is further made possible by the offset relation of the bearings 17 to the braces 15 and 16, which as a result present no interference to the described adjustment of the sustaining planes. The control of the aeroplane while in flight, is accomplished by means of the stick 44, which by being swung to the right and left in Fig. 6, rocks the lever 42 and thereby actuates the links 40 to rock the arms 38 and the shafts 36; the movement of the shafts 36 is communicated to the ailerons 35 or 35^a, the latter being operated in the well known way, to control the flight of the aeroplane. By swinging the stick 44 in directions at right angles, to the previously mentioned directions of operation, or in other words, to the right and left in Fig. 3, the horizontal rudder 47 is actuated in the conventional manner to control the machine; as previously stated, the adjustment of the vertical rudder 48 to change the directions of travel of the aeroplane is accomplished by means of the connection 46 and the foot operated rudder bar, with which the same is connected.

It will be noted that the adjustment of the sustaining planes 20 or 20^a from a normal sustaining position through arcs of not less than 90 degrees or any part thereof may be accomplished almost instantaneously by the actuation of the lever 30 and its connected parts. The main sustaining planes may, without any material loss of time, thus be quickly set in any adjustment, as the occasion may demand, or conditions make desirable, and, when necessary, may be quickly utilized for retarding and stopping the travel of the machine upon the ground. At the same time, this possibility of quick adjustment of the main sustaining planes makes it possible to bring about a quick rise of the aeroplane, so that the latter may take

off from restricted places and may be brought to a stop within such restricted places. In this way, the field of activity of the aeroplane is materially increased, without in any way complicating the mechanism thereof or making it necessary to acquire any additional skill in the operation of the machine.

Various changes in the specific forms shown and described may be made within the scope of the claims without departing from the spirit of my invention.

I claim:

1. In an aeroplane, the combination of a fuselage, a plurality of main sustaining planes pivotally mounted thereon, mechanism whereby said main planes are capable of being swung as units on their pivots from normal sustaining positions through arcs of not less than 90° and locked in adjusted positions, ailerons combined with said planes and adjusting means independent of said mechanism for adjusting said ailerons independently of said main planes.
2. In an aeroplane, the combination of a fuselage, braces extending therefrom in opposite directions, bearings carried by said braces in off-set relation thereto, shafts journalled in said bearings, main sustaining planes carried by said shafts and movable as units from normal sustaining positions through arcs of not less than 90° and combined gearing and lever mechanism operatively connected with said shafts for swinging said main planes as units from said normal positions through said arcs of not less than 90° .
3. In an aeroplane, the combination of a fuselage, braces extending therefrom in opposite directions, bearings carried by said braces in off-set relation thereto, hollow shafts journalled in said bearings, sustaining planes carried by said shafts and movable from normal sustaining positions through arcs of not less than 90° , combined gearing and lever mechanism operatively connected with said hollow shafts for swinging said planes from said normal positions through said arcs of not less than 90° , aileron shafts journalled in said hollow shafts, ailerons carried by said aileron shafts and mechanism including a stick for actuating said aileron shafts to operate said ailerons.
4. In an aeroplane, the combination of a fuselage, braces extending therefrom in opposite directions, bearings carried by said braces in off-set relation thereto, hollow shafts journalled in said bearings, sustaining planes carried by said shafts and movable from normal sustaining positions through arcs of not less than 90° , combined gearing and lever mechanism operatively connected with said hollow shafts for swinging said planes from said normal positions through said arcs of not less than 90° , aileron shafts journalled in said hollow shafts, ailerons carried by said aileron shafts, arms fixed upon said aileron shafts, a rocking lever, links pivotally connected with said arms and with said rocking lever and a stick operatively connected with said rocking lever.

In testimony whereof I have hereunto set my hand.

LAURENCE RAYNOLDS.
